UNITED STATES PATENT OFFICE.

GEORGE E. ADAMS, OF NEW BRITAIN, CONNECTICUT.

DESIGN FOR A CAP FOR SEPARABLE FASTENERS, BUTTONS, &c.

SPECIFICATION forming part of Design No. 34,309, dated April 2, 1901.

Application filed February 12, 1901. Serial No. 47,079. Term of patent 7 years.

To all whom it may concern:

Be it known that I, GEORGE E. ADAMS, of New Britain, in the county of Hartford and State of Connecticut, have invented and produced a new and original Design for a Cap for Separable Fasteners, Buttons, &c., of which the following is a specification, reference being had to the accompanying drawings, forming a part thereof.

10 In the accompanying drawings, Figure 1 is a top view of a cap-piece, illustrating my new design. Fig. 2 is a cross-section of the same.

The leading or material features of the design are the circular corrugated or fluted border extending in a horizontal plane, with a plain imperforate central convex portion or

dome projecting above the plane of the border, the outer edge of the dome merging into the inner edge of the border.

Referring to the drawings, the letter A indicates the central circular concavo-convex portion, B the border surrounding it, and C the corrugations on the border.

What I claim is—

The design for a cap-piece for separable fasteners, buttons, &c., herein shown and described.

GEORGE E. ADAMS.
